ALBERT LATHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

ROTARY CUTTER.

1,104,910.

Specification of Letters Patent. **Patented July 28, 1914.**

Application filed November 17, 1913. Serial No. 801,465.

To all whom it may concern:

Be it known that I, ALBERT LATHAM, a citizen of the United States, residing at Beverly, in the county of Essex and State of Massachusetts, have invented certain Improvements in Rotary Cutters, of which the following description, in connection with the accompanying drawings, is a specification, like reference characters on the drawings indicating like parts in the several figures.

This invention relates to rotary cutters of the type used in the manufacture of boots and shoes for the purpose of trimming the edges of the soles.

The invention aims particularly to overcome certain defects that have been encountered in using the cutters of the common commercial constructions.

For the purpose of explaining these objects more clearly, a cutter made in accordance with the usual methods has been shown in end and side elevations, respectively, in Figures 1 and 2 of the accompanying drawings.

A cutter of this type is mounted for use on the end of a rotary shaft which is driven at a very high speed, usually about 8000 revolutions per minute; and the shoe is guided for the operation of the cutter on the sole edge entirely by the hands of the workman. This trimming operation gives to the sole edge its final shape and determines the relation of the sole edge to the upper of the shoe. Consequently it determines, to a considerable extent, the style of the shoe. The proper guiding of the shoe for the trimming operation requires great care and skill on the part of the workman since the cutter trims very rapidly and any variation from an accurate guiding movement of the shoe may cause the cutter to trim into the sole edge too deeply or even into the upper, in which case the shoe will be rendered unsalable.

The cutter imparts to the sole edge in the trimming operation a transverse contour that is a complement of the transverse contour of the cutter; and for many purposes a cutter is employed that is larger at one end than at the other so as to give to the edge of the sole a rounded or beveled shape. A cutter of this character is shown in Figs. 1 and 2; and such a cutter is used in the majority of cases in trimming the shank por-

tion of the sole edge of a shoe. For this reason a cutter of the general style shown in Figs. 1 and 2 is commonly known to the trade as a shank cutter. This cutter is slotted in the usual manner in a direction parallel to the axis of the cutter and in such a manner that the front face *a* of each tooth forms an acute angle with a radial plane of the cutter; in other words, this face lies in a plane tangent to a cylinder lying within the cutter and coaxial therewith. In using a cutter of this construction it is found that the part of the edge of each tooth at the large end of the cutter begins to cut before the part of the edge at the small end of the cutter, due to the fact that the part of the cutting edge at the large end lies in a plane that is angularly in advance of the part of the cutting edge at the small end of the cutter. This relationship will be understood from an inspection of Fig. 1, in which the lines *b* and *c* indicate, respectively, the radial planes of the portions of the cutting edge at the extreme ends of the tooth *A*. The effect of this characteristic of a cutter of this style is to crowd the sole toward the small end of the cutter. This crowding action must, of course, be counteracted by the workman if he is to trim the sole edge properly, and it greatly increases the difficulty of guiding the shoe accurately for this operation. A further objection to which cutters of this character are open is the fact that the inclined part of the cutting edge of each tooth has much less clearance than the part lying more nearly parallel to the axis of the cutter. Clearance is obtained either by backing-off the teeth, as in the construction shown in Figs. 1 and 2, or else by tipping back each tooth; but the same objection is present whichever method is employed. In the backing-off operation the cutter is rotated on its axis while the backing-off tool is fed against each tooth in such a manner that it takes, at first, only a small shaving from the back of the peripheral face of each tooth. The tool is then moved slightly farther toward the axis of the cutter so that it takes off a longer shaving and this feeding movement is continued until the tool finally takes a shaving off the entire circumferential length of each tooth; the result being that the tooth is made much lower at its back edge than at its front or cutting edge. Since, however, the feeding motion of

the backing-off tool is radial of the cutter it obviously will give to each tooth a considerably greater clearance at the part of the bed of the cutter indicated, for instance, at 5 *a*, Fig. 2, than at the part indicated at *e*, Fig. 2, where the peripheral face of the tooth extends in a direction nearly parallel to the direction of the feeding movement of the backing-off tool. The part of the cutter at 10 *e*, therefore, will not cut nearly as freely as will the part at *d* and it will exert more of a dragging and rubbing action on the work than will the part at *d*. Sometimes this rubbing action is sufficient to burn, or slightly 15 discolor, the stock; and it always adds an element of resistance to the guiding movement that the operator must give to the shoe in order to cause the cutter to trim the sole, and thus makes the proper guiding of the 20 shoe more difficult. The present invention is concerned particularly with overcoming these defects.

A convenient embodiment of the invention will now be described and the manner 25 in which it is proposed to overcome these defects will be explained, reference being made to the remaining views of the drawings, in which—

Figs. 3 and 4 show in end and side elevation, respectively, a cutter blank; Figs. 5 and 6 are plan and end views, respectively, of the cutter blank showing the manner in which the slotting or milling operation is performed; Figs. 7 and 8 are plan and end 35 views, respectively, showing the manner in which the cutter is backed off; and Figs. 9 and 10 are end and side views, respectively, of the completed cutter.

The cutter blank indicated at 2 in Figs. 40 3 and 4 is made in the usual manner, the periphery of this cutter being given a transverse contour which is the complement of the contour that it is desired to impart to the edge of the shoe sole. According to the 45 preferred method of procedure, this cutter blank is next slotted. This operation is usually performed in a milling machine, the blank being clamped on a suitable spindle, and a milling cutter 4 of appropriate shape being provided, the milling cutter and blank then being moved relatively to each other to cause the cutter to form slots of appropriate depth and at the proper distance apart in the blank 2. This operation, 50 of course, forms the circumferential series of teeth of the cutter. The usual form of milling cutter may be employed for this purpose but, instead of slotting the blank in a direction parallel to its axis, which is 55 the procedure usually followed, the slotting is done at a slight angle to the axis of the cutter, as indicated clearly in Fig. 5. In other words, the milling cutter 4 usually is set with its axis at right angles to the axis 60 of the blank 2 and is fed through the blank

in a direction parallel to the plane of rotation of the cutter; while in the present case the axis of the milling cutter 4 is swung in a counter-clockwise direction with reference to the axis of the blank 2 as the parts are 70 seen in Fig. 5, until they come into about the relationship there shown and the milling cutter is then fed through the blank 2 in a direction parallel to its plane of rotation. Usually the milling cutter 4 is fed through the blank 2 until the center of the cutter has passed beyond the back of the blank; but it is preferable in many cases in forming the cutters of this invention to stop the feed of the milling cutter when its center 75 has just passed the lip *f* of the blank so that the back of the cutter will not be slotted as deeply, and consequently will be stronger than it would be otherwise. A cutter slotted in this manner instead of having the front 80 face *a* of each tooth lying in a plane tangent to a cylinder within the cutter, as in Fig. 1, will have the front face of each tooth lying in a plane tangent to a cone extending coaxially through the cutter with its base at 85 the large end of the cutter. The effect of this operation is to swing the angular position of that portion of the cutting edge of each tooth at the large end of the cutter 90 backwardly with relation to the cutting edge 95 at the small end of the cutter by an amount depending upon the angle at which the slotting is done. The relation of the angle of the slotting to the extreme difference in radial dimensions of the ends of the cutter 100 may be made such that the end portions of the cutting edge of each tooth will be brought into the same radial plane. This is the case in the completed cutter shown in 105 Figs. 9 and 10, in which the line *x*—*x* indicates a radial plane of the cutter and the points of the cutting edge of the tooth *B* at its opposite ends lie in the plane *x*—*x*. Inasmuch as the transverse contour of the 110 cutter shown is a curve, the portion of the cutting edge of the bed of the tooth between the ends does not lie in the plane *x*—*x*; but if this part of the cutter were straight, then the entire cutting edge of the bed of the tooth would lie in the plane 115 *x*—*x*. It is obvious that, if exactly this relationship were to be obtained for every change in the maximum and minimum distances of the ends of the cutting edge of 120 each tooth from the axis of the cutter, it would be necessary to vary the angle of the slotting for each variation in this difference; but inasmuch as this difference, in styles of cutters most commonly used, is confined 125 within relatively narrow limits, it is possible to adopt a mean angle of slotting that will be satisfactory for all of these more common styles. I have found from experience that an angle of 15 degrees meets these requirements; that is, when these 130

styles of cutters are slotted on this angle, the extreme portions of the cutting edge of each tooth will lie substantially in the same radial plane.

- 5 It will be evident that a cutter, constructed in accordance with this feature of the present invention and as shown for instance in Figs. 9 and 10, will not exert the crowding action on the work which has been above described in discussing the present commercial cutters, since the end portions of the cutting edge of each tooth begin to cut at substantially the same instant and the cutter does not, therefore, tend to crowd the sole in either direction axially of the cutter.

In determining the angle at which the slotting shall be done, the lip *f* of the cutter may usually be disregarded since this part of the cutter does not perform sufficient work to affect appreciably the result that is sought, and since in the more usual styles of cutters, as in the cutter shown in Figs. 9 and 10, if the angle of slotting is determined with reference to the bed of the cutter, the cutting edge of the lip of each tooth will lie substantially in the radial plane of the ends of the cutting edge of the bed of the tooth. In most instances, as in the cutter shown, the angle is determined with reference to the maximum and minimum distances of the portions of the cutting edge of the bed of the tooth from the axis of the cutter. But it is obvious that, in manufacturing special styles of cutters in which the lip does perform a considerable part of the work, the angle of milling can be adjusted on the principle above indicated so that the end of the cutting edge of the lip shall be brought into the same radial plane as the opposite end of the edge of the tooth.

The cutter, as it comes from the milling machine after being slotted, preferably is given a clearance by backing-off. This operation may be performed in a backing-off machine and by means of a backing-off tool 6, Figs. 7 and 8, of the usual construction. According to the present invention, however, the backing-off tool, instead of being fed radially of the cutter as usual, is fed at a slight angle to the radius of the cutter, as indicated in Fig. 7, this angle being such that the main component of the feeding motion is toward the axis of the cutter, while a smaller component is directed parallel to the axis of the cutter and toward the back or larger end of the cutter. The result is to remove the metal from behind the cutting edge of each tooth in a lateral direction as well as in a radial direction and, consequently, to give the cutter not only the usual radial clearance but also a slight lateral clearance. This construction avoids the rubbing and dragging action that, as above stated, is usually exerted on the work by the sharply inclined part of the bed of each tooth. The angle at

which the backing-off operation is performed may be varied as conditions require, but for the more common styles of cutters an angle of about 15 degrees is found satisfactory. This angle lies in a radial plane of the cutter and is measured from a radius of the cutter. The result just described might also be obtained by backing-off the cutter in the usual manner and then giving it a slight lateral backing-off, but the first named method is preferred since it leaves the peripheral face of each tooth of the cutter in such shape that its transverse contour will not be changed as it is ground backwardly for the purpose of sharpening the cutter. In the latter method, the lip of the cutter will be of uniform thickness from front to back so that a slight change in transverse contour would take place as the tooth became thinner after repeated shapenings. The clearance of the lip is practical as great in the former case as in the latter, since its surface recedes toward the axis of the cutter so rapidly behind the cutting edge that only a small part of its length comes in contact with the work and the lateral increase in thickness of this part of the lip is not sufficient to be appreciable.

The elimination of the crowding and rubbing actions above described in discussing the previous types of commercial cutters materially reduces the effort necessary to guide a shoe properly for the trimming operation and it eliminates the discoloring or burning action that previously has given trouble in using cutters of this general type.

Having thus described my invention, what I claim as new and desire to secure by Letters Patent of the United States is:—

1. A rotary cutter of the character described having a plurality of teeth arranged in a circumferential series, the cutting edge of each tooth comprising portions lying at different radial distances from the axis of the cutter and having portions of said edge lying at maximum and minimum distances from said axis in substantially the same radial plane, the front face of each tooth extending at an acute angle to said plane.

2. A rotary edge trimming cutter larger at one end than at the other and having a plurality of teeth arranged in a circumferential series, said cutter having slots separating adjacent teeth, the front face of each tooth lying in a plane tangent to the surface of a cone extending coaxially through the cutter with its base at the larger end of the cutter, and the portions of the cutting edge of each tooth at its opposite ends lying in substantially the same radial plane.

3. A rotary edge trimming cutter having a plurality of teeth arranged in a circumferential series, each of said teeth having the ends of the cutting edge of its bed at different radial distances from the axis of the cutter and lying in substantially the

- same radial plane, and being so shaped that its front face extends at an acute angle to said plane.
4. A rotary edge trimming cutter larger at one end than at the other and having a plurality of teeth arranged in a circumferential series, said cutter being slotted at such an angle with relation to its axis that the portions of the cutting edge of each tooth at its opposite ends lie in substantially the same radial plane, while the front face of each tooth extends at an acute angle to said plane, and the teeth of said cutter being backed off both laterally and radially.
5. A rotary edge trimming cutter having a plurality of teeth arranged in a circumferential series, the cutting edge of each tooth comprising portions lying at different radial distances from the axis of the cutter, and each tooth being so shaped that its cutting edge has both lateral and radial clearance.
6. A rotary edge trimming cutter having a plurality of teeth arranged in circumferential series, the cutting edge of each tooth comprising portions lying at different radial distances from the axis of the cutter, each tooth having both lateral and radial clearance but being so shaped that the transverse contour of its peripheral face will not be changed by the sharpening operations.
- In testimony whereof I have signed my name to this specification in the presence of two subscribing witnesses.
